SIFTPROOF BAG

Webster Noyes Baker, Baldwin, N. Y., assignor to
 Bagpak, Inc., New York, N. Y., a corporation of
 Delaware

Application July 13, 1940, Serial No. 345,318

6 Claims. (Cl. 93—35)

This invention relates to new and useful improvements in packaging containers and particularly seeks to provide a bag of rectangular cross-section, capable of standing squarely on its bottom and having its bottom walls so arranged as to be siftproof and air-tight.

Heretofore many forms of bags have been devised which tend to minimize sifting of pulv-erulent or powdered material through the bottoms thereof. However, such bags are formed in such a manner that one or more lines of fold, or even actual apertures, extending in more or less open communication with the interior of the bag are present and through which material can sift. Another difficulty heretofore encountered in the formation of "sift-proof" bags has been the inability to provide a continuous adhesive bar so disposed as to effectively seal together all of the mutually contacting surfaces of the bottom folds.

The objectionable features above referred to are completely eliminated through the use of bags constructed in accordance with this invention.

Therefore an object of this invention is to provide a bag of rectangular cross-section which is capable of standing squarely on its bottom and having its bottom walls so arranged that there are no apertures or ducts formed by lines of fold which extend into open communication with the interior of the bag.

Another object of the invention is to provide a bag of the character stated that is formed from a multiply tube blank.

Another object of the invention is to provide a bag of the character stated in which only the outer ply of the blank is slit during the formation of the bottom thereof, thereby facilitating the formation of a sift-proof bottom.

Another object of the invention is to provide a bag of the character stated in which adhesive is applied to the bottom panel portions in such a manner as to effectively seal all ducts or apertures formed during the folding operations and to seal together the mutually contacting surfaces of the bottom to thereby assure a siftproof bag.

These and other objects of this invention will become more readily apparent from the following description and with reference to the accompanying drawing in which

Fig. 1 is a perspective view of a tube blank before the bottom is folded;

Fig. 2 is a diagrammatic view showing the first stage of bottom folding;

Fig. 3 is a view similar to Fig. 2 showing the second stage of bottom folding wherein the said

walls of the tube have been folded into position to form a sift-proof bottom;

Fig. 4 is a plan view showing the manner in which adhesive is applied to the folded bottom;

5 and

Fig. 5 is a view similar to Figs. 2 and 3 showing the completely folded bottom.

Referring to the drawing in detail, the invention as illustrated is embodied in a paper bag formed from a duplex or multiply tube 5. The tube 5 is preferably formed from an outer tube 6 and an inner tube 7 and is provided with gussets 8. It should be noted that the tube 5 is preferably so formed that the longitudinal seams 10 of the inner and outer component tubes thereof are disposed in offset relation to assure a stronger bag structure as a whole. Prior to the formation of the bag bottom the outer tube 6 on one side is provided with slits 9 forming a flap 10 and on the opposite side with slits 11 forming a flap 12 which in the construction of the bottom completes the bottom formation.

It should be observed that only the outer tube 6 is provided with the slits so that in the formation of the bottom the inner tube 7 will be free of all cuts, thereby permitting the formation of a sift-proof bottom. As is customary in the formation of an automatically opening bottom, the tube 5 is provided with crease lines 13 and 14 on 20 which the tube is folded, as illustrated in Fig. 2 of the drawing, as the first operation in forming the bottom. The inner and outer plies are preferably secured together within the bottom forming area of the tube by means of triangularly shaped pasted sections 15. The flap 12 is provided with a projecting portion or tongue 12a which is held by the gripper of the bottom forming mechanism. The opposite flap 10 is held as 25 is well known in the art by means of pins which serve to assist in pulling the flaps 10 and 12 apart so that in the initial stages of the bottom formation, the end of the tube will be forced into the position shown in Fig. 2.

40 After the flaps have been pulled apart by the bottom forming mechanism the sidewall 16 is folded in a plane normal to the longitudinal direction of the bag tube. The opposite sidewall 17 is then folded in a like manner so that its marginal edge will overlap the marginal edge of the sidewall 16. An inspection of the drawing will disclose that the inner ply, not being severed, will form two triangular folds 18 and 19, and as 45 a result of such folding operation the apex of each said triangular folds will form itself into

a reentrant fold, the reentrant portion being covered by the sidewall 17. In this manner any tendency towards sifting of the packaged material would result in such a movement of the material as to require it to follow a labyrinth of such nature that actual sifting of said material will be virtually impossible. Reference to Fig. 4 of the drawing will disclose that the reentrant folds formed by an overlapping of the sidewalls 16 and 17 are effectively covered by paste and totally dam the labyrinth formed by the folds.

After the sidewalls of the bottom have been folded into an overlapped relation a bar of adhesive 20 is applied to the exposed faces of the bottom panel portions and to the faces of the flaps 10 and 12. It should be observed that the adhesive bar 20 is so shaped and so proportioned that, when the bottom is folded into final configuration, a complete adhesive seal is formed between all mutually contacting surfaces within the flap areas to thereby effectively prevent sifting of any material which might work in between certain of the overlapped portions. After the adhesive has been applied the flaps 10 and 12 are folded along crease lines 22 and 23, the flap 10 being folded into position prior to the folding of the flap 12. In order to effectively seal any ducts formed as a result of the folds of the creased lines 22 and 23, triangular sections 21 of adhesive may be included on each side of the adhesive bar 20. In forming the flaps 10 and 12, the slits defining the flaps 10 are spaced more closely than the slits defining the flap 12 so that the flap 12 effectively covers the flap 10 when the bottom is completely formed. In this manner sifting of material between the flaps 10 and 12 is effectively avoided.

Thus it will be observed that the herein disclosed invention provides a sift-proof bag of rectangular cross-section which is capable of standing squarely on its bottom and having its bottom walls so arranged that there are no apertures or ducts formed by lines of fold which extend into open communication with the interior of the bag; in which only the outer ply of the blank is slit during the formation of the bottom; and in which adhesive is applied to the bottom panel portions in such a manner as to seal together the mutually contacting surfaces of the bottom.

It is of course to be understood that various modifications of the structure disclosed herein may be resorted to without departing from the spirit or scope of the appended claims.

I claim:

1. The method of forming a square bottom sift-proof bag from a multi-ply tubular blank consisting in slitting two opposed wall portions of the outer ply of said blank to form resultant flaps; creasing said blank along lines extending transversely of the walls containing said flaps preparatory to folding the bottom; folding one of the unslit wall portions of said blank inwardly; then folding the remaining unslit wall portion inwardly, the edge thereof overlapping the edge of said first folded unslit wall portion, said folding steps thereby resulting in the formation of a substantially continuous plane surface and resulting in the projection of said flaps in opposite directions and the formation of outwardly

directed triangular apices from the adjacent portions of said inner ply and characterized by reentrant folds covered by the edge of said overlapping wall portion and located within the area defined by said flaps; then applying adhesive to portions of the plane surface thus formed; and finally folding one of said flaps over onto said plane surface and then folding the other flap over onto said first flap.

10 2. The method of forming a square bottom sift-proof bag from a gusseted multi-ply tubular blank consisting in slitting the ungusseted wall portions of the outer ply of said blank to form resultant flaps; creasing said blank along lines 15 extending transversely of the walls containing said flaps preparatory to folding the bottom; folding one of the gusseted wall portions of said blank inwardly; then folding the remaining gusseted wall portion inwardly; the edge thereof overlapping the edge of said first folded gusseted wall portion; said folding steps thereby resulting in the formation of a substantially continuous plane surface and resulting in the projection of said flaps in opposite directions, and a formation 20 of outwardly directed triangular apices from the adjacent portions of said inner ply and characterized by reentrant folds covered by the edge of said overlapping wall portion and located within the area defined by said flaps, then applying adhesive within limits defined by said flaps to portions of the plane surface thus formed and finally folding one of said flaps over onto said plane surface and then folding the other flap over onto said first flap.

25 3. In a process of manufacturing a sift-proof bag from a multi-ply tubular blank, the step of forming oppositely directed triangular apices characterized by reentrant folds from the inner ply thereof so disposed as to be covered by flap portions of the outer ply thereof.

30 4. In a process of manufacturing a sift-proof bag from a multi-ply tubular blank, the steps of slitting two opposed wall portions of only the outer ply of said blank to form resultant flaps, 45 and folding the bottom to provide a pair of triangular apices formed from the inner ply of said blank and characterized by reentrant folds and located in such position as to be completely covered by said flaps.

40 5. A sift-proof bag formed from a multi-ply tubular blank and having a folded bottom including overlapping flap portions formed by slitting two opposed walls of only the outer ply of said blank, and triangular apices formed from the unslit inner ply of said blank, and underlying the respective flap portions and being wholly covered thereby, said apices being characterized by reentrant folds and covered by overlapping edge portions of the outer ply of said blank.

60 6. A sift-proof automatic bag formed from a multi-ply gusseted tubular blank and having a folded bottom including overlapping flap portions formed by slitting the ungusseted walls of only the outer ply of said blank, and triangular apices formed from the unslit inner ply of said blank and underlying the respective flap portions and being wholly covered thereby, said apices being characterized by reentrant folds and covered by overlapping edge portions of the outer ply of said blank.

70 WEBSTER NOYES BAKER.
